DIAMOND SETTING BLOCK DEVICE

Walter W. Coffer, Jr., Houston, Tex.

Application August 3, 1948, Serial No. 42,259

2 Claims. (Cl. 125—11)

1

This invention relates to a tool-setting block, and more particularly to a setting block for use in setting a tool of an internal grinding machine.

An object of the invention is the provision of a tool-setting block whereby the diamonds can be set at a predetermined distance from a grinding rock of an internal grinding machine, thereby eliminating the old trial-and-error method.

Another object of the invention is to provide a device by means of which the point of the cutting tool can be accurately adjusted to be fed into a grinding rock of an internal grinding machine with precision in order to save the time of the operator.

A further object of the invention is to provide a tool-setting block that is extremely simple and inexpensive to manufacture.

Other objects and advantages will be apparent during the course of the following description.

In the accompanying drawings forming a part of this application, and in which like numerals are employed to designate like parts throughout the same:

Figure 1 is a fragmentary top plan view of the setting block in position on the grinding machine, according to the present invention;

Figure 2 is an enlarged top plan view of the setting block;

Figure 3 is an enlarged side elevational view of the setting block;

Figure 4 is an enlarged end view of the setting block.

Referring to the drawings in detail, the numeral 10 designates a conventional internal grinding machine provided with a bed and diamond table 11 and adjustable holder 12 for releasably holding diamond-cutting bits on tools 13. The grinding machine 10 further includes rotatable grinding rocks 9, which are used for internal grinding operations, a chuck 14, and a movable inner barrel or spindle 15 provided with a longitudinally-extending threaded socket 16 and a shoulder 8 extending inwardly from a face thereof.

For accurately setting the tools 13 at a predetermined distance, a setting block 17 is provided. The setting block 17 embodies an interengaging means on one end for connecting the setting block 17 to the barrel 15 of the machine. The inter-engaging means comprises a shaft 18 threaded exteriorly, as at 19, for a portion of its length for engagement with the socket 16 of the barrel 15. Formed integrally with the shaft 18 is an annular flange 20 adapted to be seated in the

shoulder 8 when the setting block 17 is inserted in the barrel. Formed integrally with the interengaging means and having one end secured to a face of the shaft 18 is a body 21. Positioned contiguous to the other end of the body 21 and secured thereto is a pair of sections 22 and 23 arranged in superposed relation with respect to each other. The section 22 is provided with a pair of arcuately-shaped tool-engaging faces 24, and the section 23 is provided with a pair of arcuately-shaped tool-engaging faces 26 for a purpose to be subsequently described.

The body 21 and sections 22 and 23 are provided with a pair of opposed, longitudinally-extending, cut-out portions 28 and 29, thereby effecting a reduction in the weight of the setting block 17.

In use, the centering block (not shown) is removed from the inner barrel 15 of the machine 10, and the setting block 17 is threaded therein. The setting block 17 is of a size such that after it is threaded all of the way into the barrel 15 and the inner barrel 15 moved longitudinally, the setting block 17 will be positioned in alignment with the diamond-cutting tools 13. Next, the diamond-cutting or boring tools 13 are adjusted in the holder 12 so that the tips of the tools 13 contact the complementary faces 24 and 26 of the sections 22 and 23, and the tools 13 are then tightened in place in the holder 12. After the tools 13 are adjusted and tightened in their adjusted positions, the setting block 17 is removed from the inner barrel 15 of the machine 10. The grinding rocks 9 are now ready to be dressed to size by means of the diamond-cutting tools 13 as soon as the grinding rocks 9 are placed in the machine 10. The diameters of the sections 22 and 23 are the same size as the internal bores in a work piece that are to be ground by the grinding rocks 9.

The grinding machine 10 includes the table 11 and the adjustable holder 12 for detachably or releasably holding cutting tools 13. The machine 10 is further provided with rotatable grinding rocks 9 which are adapted to be rotated by any suitable power mechanism, the rocks 9 serving to be used for various internal grinding jobs. There is provided on the machine 10 a chuck 14 which has a barrel 15 connected thereto, the barrel 15 having a threaded socket 16 and being provided with a shoulder 8. To set the tools 13 at a predetermined distance, the setting block 17 is threaded into the socket 16 of the barrel 15. The tools 13 are then adjusted until the tips of the tools 13 contact the corresponding faces of

the setting block 17 and then the tools are tightened in their proper place. Then, the setting block 17 is removed and the tools 13 can be used to dress the rocks 9 to their proper sizes prior to the use of the rocks 9 for grinding internal work pieces.

From the foregoing description and a study of the drawings, it will be apparent that I have provided a new construction. It is, of course, to be understood that I reserve the right to make such changes in the form, construction, and arrangement of parts as will not depart from the spirit of the invention or the scope of the appended claims.

I claim:

1. In a grinding machine, a bed having a rotatably mounted spindle thereon, there being a threaded socket concentric of and in said spindle, a holder mounted on the bed, diamond bits adjustably mounted in said holder, a setting block comprising a shaft provided with a threaded exterior for a portion of its length and engaging the socket in said spindle, a body secured to said shaft, and a pair of sections arranged in superposed relation with respect to each other and secured to said body, one of said sections hav-

ing a greater diameter than the other of said sections, each of said sections being provided with opposed arcuately-shaped faces concentric of said spindle, an adjacent pair of said faces being engaged by said diamond bits, the opposed side portions of said body and sections being provided with longitudinal cut-away portions for reducing the weight of said setting block.

2. The apparatus as described in claim 1 and 10 further including an annular flange arranged on said shaft contiguous to said body, and a shoulder on said spindle adjacent to said bore and engaged by said flange.

WALTER W. COFFER, JR.
